HYDRAULIC BRAKE AND COOLING MEANS
FOR HOISTING DRUMS

Lee J. Black, Beaumont, Tex.

Application November 18, 1933, Serial No. 698,718

16 Claims. (Cl. 188—264)

This invention relates to hoisting drums and particularly hoisting drums used in the drilling of wells for oil and gas.

The depth of drilled wells is constantly increasing, calling for heavier equipment which must, however, be compact, easy to install because of the limited space in the derrick and the short duration of the set up. As a consequence of the increasing depth of the wells, it has been increasingly difficult to manually control the braking action on the drums and the increasing length of the drill stem and the increasing load of pipe has reached a point where strictly manually operated brakes have about reached their capacity.

It is also a necessity of practice that the brake flanges of these drums shall be kept cool as the heat generated by the application of the brakes is very high. With these difficulties in mind, the present invention has for its object providing manual braking means for the drum and providing in addition to the manual braking means a cooling system for cooling brake flanges, and means acting in conjunction with the cooling system for furnishing fluid pressure to provide a hydraulically operated braking means.

A further object is to provide in a structure of this character, a hollow brake drum or flange, and provide an impeller disposed within the hollow brake flange and provide means whereby when the drum is rotating in one direction to cause the impeller to rotate with the drum and with the shaft upon which the drum is mounted and provide means whereby when the winding drum is rotating in an opposite direction, as for instance, when unreeling or unwinding the cable which lowers the load of pipe and the drill stem into the well, the drum will operate in a reverse direction to the movement of the impeller causing a positive circulation of water or other cooling liquid through the brake flanges of the drum itself and acting to exert a hydraulic braking action upon the drum and flanges, this hydraulic braking action acting in conjunction with the hand brake to resist the rotation of the drum and another object in this connection is to provide means acting to automatically admit water or other liquid to the circulating system of the drum flanges when the manual brake is applied and to cut off this flow of water or other liquid when the manually operable brake is released.

Other objects will appear in the course of the following description.

My invention is illustrated in the accompanying drawings, wherein:

Figure 1 is a longitudinal section of a winding drum such as is used in well drilling, this drum having applied thereto my combined hand and hydraulically operated brake mechanism;

Figure 2 is an elevation of the drum flange;

Figure 3 is an elevation of the impeller;

Referring to these drawings, 10 designates the drum shaft and 11 the body of the drum mounted upon the shaft for full rotation therewith. The drum body is provided at its opposite ends with the outwardly projecting flanges 12. A sleeve 13 surrounds the drum body between these flanges 12. The interior of the drum body 11 is cored out at 14. Surrounding each end of the shaft outward of the respective flanges 12 is a sleeve 15 which forms the extended hub of an impeller, the blades of which are designated 16, this impeller being shown in Figure 3. Keyed upon each 75

impeller hub 15 is a sprocket wheel. These sprocket wheels are of different diameters for the purpose of driving the drum at different speeds and one of these sprocket wheels is designated 17 and the other 18, the sprocket wheel 17 being larger in diameter than the sprocket wheel 18. Keyed upon the shaft 10 for rotation therewith but for longitudinal movement with reference thereto are the two clutches 19 and 20, the clutch 19 coacting with the hub of the sprocket 80

wheel 17 and the clutch 20 coacting with the hub of the sprocket wheel 18. Thus when the clutch element 19 is engaged with the sprocket wheel 17, the shaft 10 will rotate at one speed as will the impeller 16 and when the clutch 20 is engaged with the sprocket wheel 18, the shaft will rotate at another speed as will the corresponding impeller 16. When both clutches 19 and 20 are disengaged, however, the shaft 10 will rotate freely in a reverse direction to the direction of 85 movement of the sprocket wheels 17 and 18 and under these circumstances, of course, the impellers 16 being connected with the power driven sprocket wheels 17 and 18 will rotate in a reverse direction.

Mounted opposite each drum flange 12 is a brake flange designated generally 21. This brake flange is angular in cross section as shown in Figure 1 so as to provide a peripheral web 22 and an end web 23, this end web 23 being parallel to 105 and confronting the drum flange 12. Bolts 24 pass through the peripheral web 22 into the drum flange 12 to thus hold the brake flange against the drum flange. The periphery of the brake flange is reduced in diameter to provide a seat for the 110

brake band 25, there being, of course, a brake band for each brake flange. The inner portion of each web 23 is formed with an outstanding annular flange 26 formed to provide a packing recess 8 between the impeller hub 15 and the flange 26 within which is disposed the packing 27. A packing gland 28 surrounds the hub 15 and bears against this packing 27 and is held in place by screws 29 or other suitable means as shown in 10 Figure 1. Between the ends of the drum body 11 and the confronting ends of the hubs 15 packing 30 is disposed.

It will be seen that the blades of each impeller 16 are disposed within a chamber designated generally 31. It will likewise be seen from Figure 3 that these impeller blades are curved in the direction of rotation of the sprocket wheels 17 and 18. The confronting or outside face of each plate flange 12 as shown in Figure 2 is also 20 formed with a series of curved ribs 32 extending outward from an annular rib 33, each brake flange adjacent its periphery being also formed with an annular rib 34 through which the holes for the bolts 24 pass. This annular rib 34 extends into 25 an annular recess in the brake flange 22.

One end of the shaft 10 as shown in Figure 1 is formed with a bore 35 which swivelly is connected to a water inter inlet pipe 36. The opposite end of the shaft is formed with an outlet bore 37 swivelly connected to an outlet pipe 38. The swiveled connections may be of any suitable form but, as illustrated, each pipe 36 or 38 is provided on its inner end with a head 39. The end of the shaft is recessed to receive this head and screw-threaded to receive a nut 40 which bears against the head. This nut is formed to provide a packing space for a packing 41 held in place by a gland 42. It will thus be seen that the shaft 10 may rotate freely with relation to 40 the pipes 36 and 38. The inlet bore 35 at its inner end is connected to a radially extending passage 43 which is flared at its outer end to the surface of the shaft 10. The drum is formed with a corresponding radial passage 44. Disposed 45 within the passage 44 is a pipe section 45 closed at its outer end and having screw-threaded engagement with the drum.

Disposed with its headed end within the flared end of the opening 43 is a pipe section 46 and packing 47 is disposed between the headed end of the pipe section 46 and the adjacent end of the pipe section 45. These telescopic pipe sections 45 and 46 have apertures 48 which discharge into a chamber 49. An aperture 50 leads from the chamber 49 out through the wall of the flange 12 and discharges into the impeller chamber 31.

Diametrically opposite the opening 50, the end wall of the drum 11 is formed with a relatively deep recess 51. The opposite end wall of the drum is also formed with a corresponding recess 51. Extending between these recesses 51 in the opposite end of the drum is a pipe 52 which connects these two recesses, this pipe being held in place by the packing glands 53 which bear against the packing 54. Thus communication is established between the impeller chamber of one brake flange and the impeller chamber of the opposite brake flange. The right hand impeller chamber in Figure 1 is also connected to the outlet bore 37 by the telescopic pipes 45 and 46 as was previously described.

It will be seen that the pipes 45 constitute glands bearing against the packing 47 and in order to provide for access to these glands so as 70 to remove them and renew the packing, the sleeve 75

13 is provided with openings immediately in alignment with the headed ends of the glands or pipes 45 which openings are normally closed by the plugs 55.

The brake bands 25 are operated by any suitable means. I have shown for this purpose, however, a rock shaft 56 which is connected to the brake bands in the usual manner, common in this type of apparatus. This brake shaft carries the brake handle 57 whereby the brakes may be manually applied. It is also designed that when the brakes 25 are applied by means of the handle 57, water shall be allowed to flow into the pipe 36 from a supply pipe 58 and that when the brake bands are released, the water shall be cut off from the pipe 36 and allowed to flow through a waste pipe 59. To this end I have provided a three-way valve designated 60 and shown in dotted lines in Figure 1, this valve having on it the arm 61 connected by a link 62 to an arm 63 on the brake shaft 56.

From the construction shown in Figure 1, it will be seen that when the handle 57 is turned to rotate the shaft 56 in the direction of the arrow in Figure 1, the arm 61 will be moved to cause 100 the three-way valve to connect the pipes 58 and 36 and that as the shaft 56 is rocked in a reverse direction, the arm 61 will be pulled downward in Figure 1, thus cutting off the supply of liquid to the pipe 36 and directing it out through the pipe 59.

The operation of this mechanism is as follows:—

The clutches 17 or 18 are thrown in when it is desired to wind up the cable on the drum and lift 110 the drill string and pipe from the well but when it is desired to lower the pipe and drill string into the well, both clutches are released and the weight of the drill string or pipe, that is, the weight of the load on the cable, acts to rotate 115 the drum reversely, the drum being prevented from too rapid rotation by the application of the hand brake 25 and by the resistance offered by the impellers which are rotating at this time in the direction of the arrow in Figure 3 and in a 120 reverse direction to the direction of rotation of the drum. At this time, when both clutches are thrown out and the drum is unwinding, the unwinding movement is obstructed, as before stated, by the brake bands 25 and liquid flows into the 125 pipe 39 through bore 35 through the passage 43 to the port 50 around the left hand brake flange or left hand impeller chamber, then through the cross pipe 52 of the right hand impeller chamber, then out through the port 50 thereof through the 130 pipes 45 and 46 thereof into the bore 37 and out through the pipe 38. This liquid cools the brake flanges which would otherwise become overheated by the application of the brake bands and the rotation of the impellers in the opposite direction to the rotation of the drum causes a hydraulic braking action which assists the brake bands in retarding the downward movement of the drum. The greater the application of the brake bands, the greater the flow of liquid 140 through the drum, the greater its cooling action and the more does it obstruct the rotation of the drum through the action of the impeller blades.

It will be understood now that the impeller blades rotate at all times with the sprockets 17 and 18. When one or the other of the clutches 18 or 19 is thrown in to cause a rotation of the drum in a direction to wind up the cable, the impellers then move with the drum and with the brake flanges, thus offering no impediment to 150

the free rotation of the drum and the liquid that is within the impeller chambers 31, of course, rotates with the drum and with the impellers in the same direction. It is only when the drum 5 is unwinding and the clutches 19 and 20 are thrown out that the impellers then positively rotate in the direction reverse to that of the drum and act to hydraulically brake the drum and cause a positive circulation of the liquid through 10 the brake flanges from the pipe 36 to the pipe 38. The construction which I have illustrated is particularly simple and is very readily assembled. It will be noticed that the hollow brake flange designated generally 21 bolts on to the flange 12 15 of the main drum, the hollow brake flange forming one wall of the impeller chamber and the main brake flange forming the opposite wall of the chamber. This enables the ready assembly of the impeller within the brake flange. In this 20 way, it is a simple matter to renew the packing and prevent leakage. This is done by unbolting the brake flange 21 from the drum flange 12. This uncovers the interior packing between the runner hub and the hub of the main drum flange. 25 By the removal of the sprocket, it is an easy matter to repack around the extended hub of the runner.

While I have heretofore referred to the impellers as rotating continuously and the sprocket wheels as rotating continuously, it is to be understood that even though the sprocket wheels and impellers are not rotating, yet if the drum be allowed to run free under the unwinding action of the cable, there will be relative rotation between the drum and the impellers, the impellers standing still and the drum rotating and this will cause a circulation of water or other cooling liquid through the brake flanges of the drum and act to produce a hydraulic braking action between the drum and the impeller. It will thus be seen that the braking action would be had, regardless of whether the impellers were rotating or not.

While I have illustrated the blades of the impellers as being curved and the confronting ribs on the brake flanges as being curved, it is not necessary to curve the impeller blades nor the ribs in order to produce a braking action. If both were straight, however, clearance would have to be greater between the edges of the impeller blades and the ribs in order to allow the fluid to pass. The curved blades will allow the fluid to pass continuously at some point in the curve when the drum is running in reverse direction to the impellers. While this would produce less braking action, it would, however, also produce less vibration.

I claim:

1. A winding drum having a brake portion enclosing a space for cooling liquid, a bladed impeller disposed within the space, power operated means for rotating the drum and the impeller together in the same direction, and means for releasing the drum from the power operated means to permit it to rotate in an opposite direction to the direction of rotation of the impeller whereby to cause the impeller to act as a hydraulic brake on the drum.
2. A winding drum having a brake portion enclosing a space for liquid, a bladed impeller disposed within the space, power operated means connected with the impeller for rotating it constantly in one direction, manually controlled means for operatively connecting the drum to the impeller and the power operated means for

common rotation therewith in one direction or releasing the drum to permit it to rotate in an opposite direction to the direction of rotation of the power operated means and impeller to thereby cause the impeller to act as a brake on the drum.

3. In a draw works, a shaft, a drum mounted for rotation with the shaft and having a brake flange formed to provide a space for cooling liquid, an impeller mounted upon said shaft for rotation independently thereof and having blades disposed within said space, power operated means for rotating said impeller, a clutch means mounted upon the shaft for engaging the shaft with the power operated means or disengaging it therefrom.

4. In a draw works, a shaft, a drum mounted upon the shaft and having a brake portion enclosing a chamber for cooling liquid, a hand operated brake operatively engaging said brake portion of the drum, an impeller mounted upon the shaft for free rotation with relation thereto and having blades extending into the chamber, power operated means for rotating the impeller in one direction, and a clutch mechanism for connecting the shaft to or disconnecting it from said power operated means.

5. In a draw works, the combination with a winding drum having a brake flange, and a manually operable brake for controlling the unwinding movement of the drum, power operated means for rotating the drum, clutch means for connecting the power operated means to the drum or disconnecting it therefrom, and a hydraulic brake automatically operated to resist the rotation of the drum when the drum is disconnected from the power operated means and is rotating in a direction opposite thereto.

6. In a draw works, a shaft, a winding drum mounted thereon and having a brake flange, the brake flange enclosing a chamber extending concentrically to the shaft, the shaft having a liquid inlet and a liquid outlet operatively connected to said chamber to discharge cooling liquid thereinto and take cooling liquid therefrom, an impeller having blades disposed within the chamber, driving means for the impeller, means for clutching the driving means to the shaft to cause the drum and impeller to rotate in the same direction and for unclutching the shaft to permit the shaft and drum to rotate in an opposite direction to the direction of movement of the impeller and driving means, and manually operable braking means engaging the periphery of the brake flange.

7. In a draw works, a drum shaft, a drum mounted upon the shaft for rotation therewith and having a brake flange, hand braking mechanism engaging the brake flange, the brake flange being formed to provide a fluid chamber concentric to the shaft, a rotor disposed within the fluid chamber, means for rotating the drum and rotor together, or disconnecting the drum from the rotor, and fluid circulating system supplying cooling fluid to the interior of the chamber whereby to secure a braking action by the rotor on the drum when the drum is operated separate from the rotor.

8. In a draw works, a hoisting drum having a brake flange, the flange enclosing a fluid chamber, means for circulating fluid through the fluid chamber, a rotor within the fluid chamber, power operated means for rotating the rotor in one direction, clutch means for rotating the drum with the rotor and in the same direction or for dis-

- connecting the rotor from the drum to permit the drum to rotate in a reverse direction to the rotor whereby to cause the rotor to act as a hydraulic brake on the drum. 80
- 5 9. In a draw works, a shaft, a drum body mounted thereon having an outwardly extending annular flange, a brake flange forming part of the drum and abutted against the first named flange and attached thereto, the drum flange, 85 body of the drum and the brake flange defining a chamber for cooling liquid, means for circulating cooling liquid through said chamber, an impeller having blades disposed within said chamber, a gear wheel operatively engaged with said 10 impeller to rotate it, means for connecting the drum to the gear wheel or disconnecting it therefrom, and hand braking means applied to the periphery of the braking flange. 90
- 10 10. In a draw works, a shaft, a drum body mounted upon the shaft and having an outwardly projecting annular flange, a brake flange detachably engaged with the drum flange, the brake flange, the drum flange and the end of the body defining an annular cooling chamber concentric 95 to said shaft, an impeller having a hub loosely surrounding the shaft and extending through the end wall of the brake flange, the impeller having blades disposed within the chamber, a power actuated element engaged with the hub of the impeller for common rotation, clutch means for engaging said element with the shaft or disengaging it therefrom, hand operated braking mechanism applied to the exterior of the brake flange, and means for causing a circulating of cooling 100 liquid through said chamber. 100
- 15 11. In a draw works, a shaft, a drum body mounted upon the shaft and having an outwardly projecting annular flange, a brake flange detachably engaged with the drum flange, the brake flange, the drum flange and the end of the body defining an annular cooling chamber concentric to said shaft, an impeller having a hub loosely surrounding the shaft and extending through the end wall of the brake flange, the impeller having 105 blades disposed within the chamber, the end face of the drum flange being formed with ribs extending toward the periphery of the drum flange, a power actuated element engaged with the hub of the impeller for common rotation, clutch means for engaging said element with the shaft or disengaging it therefrom, hand operated braking mechanism applied to the exterior of the brake flange, and means for causing a circulation of cooling 110 liquid through said chamber. 115
- 20 12. In a draw works, a shaft having a liquid inlet bore at one end and a liquid outlet bore at the opposite end, a drum mounted upon the shaft and having two drum flanges, the drum and flanges being formed to provide two chambers extending concentrically to the shaft, means for communicatively connecting the inlet bore of the shaft with one of said chambers, connecting the outlet bore of the shaft with the other of said 120 chambers and connecting the chambers with each other, impellers mounted in each chamber, each impeller having a hub portion extending out of the corresponding chamber and having blades 125
- 25 disposed within the corresponding chamber, independent means for driving each of the impellers in the same direction, independent means for connecting each of said driving means to the shaft or disconnecting it therefrom whereby the shaft, the impeller and the drum may be driven in one direction or the drum permitted to rotate in a direction reverse to the direction of movement of the impellers, and hand operated braking means applied to the brake flanges. 130
- 30 13. In a draw works, a shaft, a winding drum mounted upon the shaft, the winding drum being formed to provide brake flanges enclosing cooling chambers, hand braking mechanism applied to the periphery of said brake flanges, means controlled by said hand braking mechanism for causing a circulation of liquid through one end of the shaft successively through the chambers and out through the other end of the shaft, impellers mounted within each chamber and having hubs extending concentrically to the shaft out through said chambers, independent driving means engaged with said impellers and rotating said impellers in a constant direction, and means for connecting either of said driving means with the shaft or disconnecting the shaft therefrom to permit the shaft and the drum to rotate in a direction reverse to that of the impellers. 135
- 35 14. In a draw works, a drum having a peripheral flange, a brake flange having a peripheral portion abutting against said drum flange and detachably held thereto and having a web extending parallel to the drum flange and end of the drum but terminating short of the shaft, the brake flange and drum flange together enclosing 140 an annular chamber concentric to the shaft, an impeller having a hub surrounding the shaft and extending outward between the shaft and the end of said web and having blades disposed within the chamber, packing between said web and the hub, a packing gland engaging said packing and disposed exteriorly of the web, a drive wheel engaged with the hub of the impeller to rotate it in a constant direction, a clutch on the shaft and adapted to connect the shaft with the drive wheel 145 or disconnect it therefrom, and means for causing a circulation of liquid through said chamber. 150
- 40 15. A winding drum having a brake portion enclosing a space for cooling liquid, a bladed impeller disposed within the space, power operated means for rotating the drum and the impeller together in the same direction, and means for releasing the drum from the power operated means to permit it to rotate relative to the impeller whereby to cause the impeller to act as a hydraulic brake. 155
- 45 16. A winding drum having a brake portion enclosing a space for cooling liquid, a bladed impeller disposed within the space, means for rotating the drum and the impeller together in the same direction, and means for releasing the drum from the power operated means to permit it to rotate freely relative to the impeller whereby to cause the impeller to act as a hydraulic brake for the drum. 160

LEE J. BLACK.
